UNITED STATES PATENT OFFICE

MAURICE AUGUSTE EUGÈNE LEBLANC, OF SURESNES, FRANCE, ASSIGNOR, BY MESNE ASSIGNMENTS, TO GENERAL ELECTRIC COMPANY, A CORPORATION OF NEW YORK

MERCURY VAPOR RECTIFIER

Application filed August 15, 1927, Serial No. 213,166, and in France September 21, 1926.

This invention relates to mercury vapor rectifying and the like apparatus and has for its main object to provide improved arrangements for starting or lighting up apparatus 5 of this character in which a movable starting or lighting up electrode device is employed.

In order to start or light up mercury vapor rectifying apparatus, for example, a movable electrode mounted at the extremity of a 10 bimetallic element has been employed, the bimetallic element being arranged to be deformed when heated in any suitable manner so as to move the electrode out of the mercury cathode of the apparatus, in which it is 15 immersed when at rest, and thereby start or light up the apparatus upon breaking contact between the mercury cathode and movable electrode, it being understood that a current is caused to flow between the cathode and 20 movable electrode when it is required to start the apparatus.

The present invention is applicable essentially to this particular system of starting or lighting up and is concerned more especially 25 with the constructional form of the movable electrode device and with the protection of the latter against various causes of deterioration on the one hand, and on the other hand with various electrical circuit arrangements 30 permitting the employment of the improved movable electrode device.

As regards the practical constructional form of the movable electrode device the bimetallic portion thereof is protected against 35 direct contact with ionized vapor, so as to avoid all risk of deterioration this being attained, for example, by means of a screen or screens of insulating material and the electrode portion itself, which is arranged to be 40 immersed in the mercury cathode when at rest, consists of material, such for example as tungsten, which is not volatilized under the action of the cathode glow. The electrode portion may be arranged in such a manner 45 that it is disposed just at the surface of the mercury, for small differences of potential, thus permitting the cathode glow to be fixed and thus stabilize the main arc.

As regards the electrical circuit arrangements 50 applicable for use with the movable

electrode device a device is employed for preventing the flow of continuous current in the circuit of the starting or lighting up electrode device, in the event of the starting or lighting up arc being produced with the movable 55 electrode device as the cathode, on the one hand and on the other hand for placing the whole of the movable electrode at the same potential as the cathode when once the main arc has been struck. This result can be attained, either by employing a suitable relay for breaking the starting or excitation circuit when the apparatus is started or lit up and consequently preventing the flow of continuous current which would tend to be established in the starting or excitation circuit, or by inserting in this circuit a condenser alone or a condenser accompanied by an induction coil. In the case where a relay is employed in the starting or excitation circuit of 60 apparatus of relatively great power a device is employed for starting at low load and permitting the closing of the output circuit of the apparatus only when the main arc is struck.

The devices utilized for the purposes mentioned above may be constituted either by circuit breaking or the like devices, or by auxiliary electrical systems, casings or gratings provided on the exterior or in the interior of the projecting anode arms of the apparatus, these devices being controlled by systems of suitable relays in such manner as to prevent starting under load.

In order that the invention may be clearly understood it will now be described by way of example, with reference to the accompanying drawings, in which:—

Figure 1 is a view of an improved constructional form of movable starting or lighting up electrode device applied to mercury vapor rectifying apparatus.

Figure 2 is a diagrammatic view of improved circuit arrangements for starting rectifying apparatus for relatively small currents at relatively low pressure.

Figure 3 is a diagrammatic view of modified circuit arrangements suitable for rectifying apparatus of comparatively great ca- 100

pacity and provided with a maintaining circuit through a permanent shunt.

Figure 4 is a diagrammatic view of further modified circuit arrangements suitable for rectifying apparatus of comparatively great capacity and provided with a maintaining circuit through special electrodes, and

Figure 5 is a view of a rectifying apparatus provided with a starting or excitation circuit having a condenser therein.

Referring first to Figure 1, the lead 1 for the starting or excitation current is mounted in a projecting portion of the lateral wall of the mercury vapor rectifying apparatus, 15 and is connected at 2 to one extremity of a bimetallic element 3 which is connected at its other extremity 4 to a tungsten starting electrode 5 covered with glass for a considerable portion of its length intermediate its 20 extremities as illustrated. The lower uncovered portion 6 of the bimetallic element 3 is normally in contact with the mercury in the apparatus and it is the breaking of this contact which effects the striking of an 25 arc for starting or lighting up the apparatus. The whole of the bimetallic element together with its connections with the lead 1 and electrode 5 is protected from direct contact with the ionized vapor by an insulating tube 7, 30 of glass for example, the lower extremity of which is supported by a flange 8 provided on the covering of the electrode 5. It will be evident that, if a current sufficient for heating the element 3 is caused to flow in a circuit 35 including the starting electrode 5 and the cathode of the apparatus, the element 3 will be deformed and the circuit will be broken down between the portion 6 and the mercury, thus striking an arc for starting or 40 lighting up the apparatus, it being understood that the play of the electrode 5 and insulating tube 7 as a whole is arranged to be sufficient to permit the deformation of the element 3 to the required extent. The 45 general elevation of the temperature of the rectifying apparatus during operation also causes the element 3 to be heated and deformed so that the electrode 5 is raised but this deformation is not of importance. It is 50 however, of advantage to adjust the element 3 so that when the rectifying apparatus is operating at a relatively small difference of potential, that is to say at a relatively low temperature, the portion 6 of the electrode 55 5 is just at the surface of the mercury, thus permitting the cathode glow to be fixed on the surface of the mercury and increase the stability of the main arc.

Before describing various electrical circuit arrangements (Figures 2 to 5) for use in connection with the bimetallic starting element, it should be observed that the starting or lighting up of the rectifying apparatus is effected by breaking contact between the 65 mercury and the electrode 5 and thus cut-

ting off the current heating the bimetallic element, this current usually being alternating in character as the employment of continuous current for this purpose introduces complications. Contact is therefore broken 70 sometimes with the mercury and sometimes with the electrode 5 as the cathode, and the circuit arrangements utilized should therefore be capable of selecting between these two cases, and main arc of the rectifying apparatus should only be able to be struck 75 when the cathode glow is on the mercury.

Moreover experience has shown that when the main arc of the rectifying apparatus has been struck the starting electrode 3 should 80 be placed at the same potential as the cathode, if it is desired to avoid all danger of striking a cathode glow on the metallic portions of the starting electrode.

Circuit arrangements for use with rectifying apparatus for small currents at low pressure are illustrated in Figure 2 and referring now to this figure it will be observed that the anodes 10 of a mercury vapor lamp 9 are arranged to be energized by an autotransformer 11 which is itself energized through the leads 12. A winding 13 is provided on the core of the autotransformer 11, this winding being connected on one hand to the cathode 14 of the lamp and on the other hand to a bimetallic starting electrode device 15 through the two contacts 16 of a relay and through a resistance 17. The cathode 14 of the lamp 9 is moreover connected to a self inductance 18 arranged in series with the winding 19 of the relay. When the mercury vapor lamp is not operating and the autotransformer 11 is energized, alternating current is supplied to the circuit 13, 14, 15, 16, 17 and the bimetallic starting electrode device 15 is heated, thus causing contact 95 between the electrode 15 and the mercury to be broken.

When the mercury is the cathode at the moment of breaking contact, and if the phase is favorable, the lamp 9 is started normally continuous current being supplied to the winding 19 of the relay with the result that the two contacts 16 are opened so as to cut 110 off the starting or lighting up current and permit the bimetallic starting electrode device 15 to assume the same potential as the cathode. The bimetallic starting electrode device 15 cools and comes into contact with the mercury and fixes the cathode glow. If on the contrary the phase is unfavorable, the bimetallic starting electrode 15 becomes cold, and comes into contact with the mercury, and the starting or excitation circuit being yet 115 closed new break of contact is effected.

When however the electrode 15 is the cathode at the moment of breaking contact and if the phase is favorable, continuous current is supplied to the circuit 15, 17, 16, 13, 18, 19 but is cut off at the two contacts 16, which are 120 125 130

closed at once, and the same process continues to be carried out until normal starting is effected.

It will be observed that the relay 16, 19 effects the selection between the normal and reverse starting or lighting up and on the other hand places the electrode 15 at the same potential as the cathode when normal starting is effected.

10 It is to be observed that the contacts 16 of the relay should be on the one hand capable of cutting off all the continuous current load on the one hand and on the other hand of offering a resistance to the passage of current which is sufficiently small so as not to limit the starting or excitation current even if a winding 13 of very low pressure is employed.

15 It has been assumed until now that the relay 16, 19 and self inductance 18, are separate from one another but they could be constructed as a single device by utilizing the flux due to self inductance 18 to move the contacts 16 which may be of any desired form.

20 The circuit arrangement illustrated in Figure 2 which is applicable to rectifying apparatus for small currents at low pressure fails in the case of rectifying apparatus of 30 comparatively great capacity. In fact, if it were used in the latter case without modification, and the cathode glow were formed on the starting electrode 15 when starting, the total current supplied by the rectifying apparatus would be liable to flow through the starting electrode 15 and this current would have to be cut off by the contacts 16, whereby rapid deterioration of both the contacts 16 and electrode 15 would be caused.

25 It is therefore necessary, in the case of apparatus of comparatively great capacity, to effect the striking of the arc of comparatively small difference of potential through an auxiliary circuit, and to permit the closure of the continuous current circuit only after having normally obtained the striking of the arc.

30 In Figures 3 and 4 two circuit arrangements of this character are illustrated as applied to rectifying apparatus provided with a maintaining circuit through a permanent shunt (Figure 3) and on the other hand to rectifying apparatus provided with maintaining electrodes.

35 In Figure 3, the autotransformer 20, which is illustrated as a monophase transformer, is arranged to energize the two anodes of the mercury vapor lamp 21. A winding 22 is provided on the core of the transformer 20 for energizing the cathode and starting electrode circuit through a resistance 23 and a relay provided with two opening contacts 24.

40 A resistance 25, serving as a shunt for maintaining the main arc, is connected across 45 the apparatus and is arranged in series with

a winding 26 provided for actuating the contacts 24.

45 In the output circuit of the rectifying apparatus a circuit breaking device 27 is inserted which is adapted to be actuated upon 70 the passage of alternating current at a difference of potential equal to the difference of pressure between the anodes and the neutral point of the transformer 20. The actuating circuit of the circuit breaking device 27 may 75 be closed either by the contacts 28 of a maximum current relay arranged in series in the output circuit or by the opening contacts 29 controlled by the winding 26. It will be observed that with this circuit arrangement 80 the starting or lighting up process is similar to that described with reference to Figure 2 but, owing to the contacts 29, it is impossible to close the circuit breaking device 27 when the rectifying apparatus is not suitably started 85 on its shunt.

Moreover, in case of the failure of the supply of alternating current, the first effect of the re-establishment of the pressure is to actuate the circuit breaking device 27, thus rendering impossible the starting of the apparatus on load.

50 In Figure 4 the rectifying apparatus is illustrated as being provided with a maintaining circuit having special electrodes. A 95 three-phase transformer 30 is arranged to supply the main anodes 31 of the lamp, and a separate transformer having double winding 32 has its primary winding energized for example from two of the supply terminals 100 of the transformer 30. The secondary winding of the transformer 32 is connected at its extremities to the maintaining anodes 33 of the apparatus through two induction coils 34 which may cooperate with the same magnetic circuit if desired, the neutral point of the secondary winding being connected to the cathode 35 through an induction coil 36 controlling two pairs of contacts; an opening pair 37 and a closing pair 38.

55 The pair of contacts 37 are included in the starting or excitation circuit comprising a winding 39 mounted on the maintaining transformer 32 and a resistance 40.

60 On the other hand, included in the output circuit are a maximum relay 41 and a contact device 42 provided with a closing auxiliary contact 43. The contact device 42 is provided with a controlling circuit comprising a resistance 44 and two push buttons, one 45 120 for closing the other 46 for opening.

65 The operation of the apparatus illustrated in Figure 4 is as follows:—

The process of starting or lighting is carried out as before by means of the maintaining circuit, and when the apparatus is suitably started, the winding 36 opens the contacts 37, consequently insulating the starting electrode device, and closes the contacts 38, thus permitting the closing of the con- 130

tact device and it is sufficient for this purpose to press the button 45. The closing coil attracts the armature, which closes the auxiliary contact 43 shunting the push button 5 and inserting the resistance 44 in the circuit.

The circuit may be broken, either by actuating the push button 46, or, in case of too great a current, by the action of the maximum relay 41. If the supply current fails, 10 the contact device 42 opens, as is also the case when the maintaining circuit is accidentally broken. In any event the apparatus cannot be started while the continuous current circuit is closed.

15 In the case of two or more rectifying apparatus arranged in parallel with their cathodes interconnected if it is desired to employ one contact device only for protective purposes each rectifying apparatus may be 20 provided with similar starting devices, but it is then necessary to interpose in series in the closing circuit of the single contact device all the contacts corresponding to 38. All the lamps should be lighted up so that 25 the contact device can be closed on the external circuit.

It will be evident that the contact device can be operated by an automatic device, on condition always, that such a device, only 30 permits the contact device to close when all the maintaining circuits are in operation.

It was supposed above that the closing winding of the contact device was employed in shunt with the continuous current circuit, 35 but a closing winding in series with the maintaining circuit, may be employed which permits the omission of the contacts 38, the latter arrangement being recommended in certain cases, in particular where a variable pressure is employed.

An external casing device or internal grating device may still be employed in the apparatus for preventing starting under load it being sufficient to provide each projecting 45 anode arm of the apparatus either with an external or internal grating.

In order to prevent starting under load it is sufficient to employ a system of relays similar 50 to those described above in order to place the casings or gratings at the same potential as the cathode so that the maintaining circuit is not energized and to the potential of the corresponding anodes as soon as the maintaining circuit is energized. This arrangement is applicable in particular to high tension rectifying apparatus which always functions at a low temperature, a circumstance favoring the employment of casings and gratings.

60 The arrangements described above render impossible the closure of the continuous current circuit, when the starting of the rectifying apparatus is not suitable. An arrangement for permitting starting under load without permitting continuous current

to traverse the starting electrode may also be provided, it being sufficient for this purpose to interpose in the starting circuit a condenser in series with a self inductance in order to diminish its impedance.

Figure 5 illustrates such an arrangement. The autotransformer for supplying current to the lamp 47 is provided with a starting winding 48 connected to the starting electrode through a winding 50 and condenser 49. 75 It will be observed that in these conditions, the starting electrode will be operated until continuous current is established in the cathode circuit, inasmuch as it cannot be established in the lighting circuit because of the condenser. A relay (not illustrated in Figure 5) may be employed for breaking the starting circuit and for placing the starting electrode at the same potential as the cathode. 80

It will be evident that the invention is not 85 limited to the particular arrangements hereinabove described which may be varied as required to suit particular requirements.

Claims:

1. In vapor rectifying apparatus, the combination of an auxiliary electrode, bi-metallic means for actuating said electrode and means including a tubular member for protecting said electrode and said bi-metallic means from the action of the ionized vapor within the 95 apparatus, said tubular member being mounted to permit deformation of said bimetallic means.

2. In vapor rectifying apparatus, the combination of an auxiliary electrode, bi-metallic 100 means for actuating said electrode and insulating means including a tubular member surrounding said electrode and said bi-metallic means and protecting same from the ionized vapor within the apparatus, said tubular 105 member being mounted to permit deformation of said bimetallic means.

3. In vapor rectifying apparatus, the combination of an auxiliary electrode composed of tungsten, bi-metallic means arranged to 110 support and actuate said electrode, an insulating casing surrounding said bi-metallic means all mounted to permit deformation of said bi-metallic means and an insulating covering for a portion of said electrode.

4. In vapor rectifying apparatus, the combination of an auxiliary electrode made of tungsten, bi-metallic means for supporting and actuating said electrode, and insulating covering for said electrode and insulating 120 means surrounding said bi-metallic means.

In testimony whereof I affix my signature.

MAURICE AUGUSTE EUGÈNE LEBLANC.
